Primary Examiner — Catherine A Tuttle(74) *Attorney, Agent, or Firm* — Michael A. Catania; Sonia Lari; Rebecca Hanovice(57) **CLAIM**

The ornamental design for a golf ball, as shown and described.

DESCRIPTION

FIG. 1 is a top perspective view showing our new design for a golf ball with a red center line and parallel blue lines;

FIG. 2 is a top plan view thereof;

FIG. 3 is a side elevation view thereof;

FIG. 4 is a bottom plan view thereof;

FIG. 5 is another top plan view thereof presented to show the area of enlargement in FIG. 6; and,

FIG. 6 is an enlargement of area 6 of FIG. 5.

The drawing is lined for color.

The broken lines denoting the circumscribed area in FIG. 5 and depicting circular and linear surface details are for illustrative purposes only; and form no part of the claimed design.
